S. HARROLD

WRIST MIRROR

Filed Nov. 19, 1921

Fig. 2.

Inventor
Sherman Harrold.

By

Lacey & Lacey, Attorneys

UNITED STATES PATENT OFFICE.

SHERMAN HARROLD, OF HARTFORD CITY, INDIANA.

WRIST MIRROR.

Application filed November 19, 1921. Serial No. 516,409.

To all whom it may concern:

Be it known that I, SHERMAN HARROLD, a citizen of the United States, residing at Hartford City, in the county of Blackford 5 and State of Indiana, have invented certain new and useful Improvements in Wrist Mirrors, of which the following is a specification.

This invention is a novel article which I term a wrist mirror and the object of the invention is to provide a device which may be worn upon the wrist at all times and will be attractive in appearance and furnish the wearer with a small mirror capable of use 15 for all purposes for which any mirror may be used. The invention is illustrated in the accompanying drawings and will be herein-after fully set forth.

In the drawings—

20 Figure 1 is a perspective view of a wrist mirror embodying my invention;

Fig. 2 is a longitudinal section of the same.

In carrying out my invention, I employ a base block 1 which may be of any preferred material and may be given any desired configuration. The under side of the base block is dished, as shown at 2, so that it will fit comfortably upon the wrist without irritating the same and the edges of the base block are preferably beveled, as shown at 3, so as to impart an attractive appearance to the block and also reduce wear upon the securing strap or ribbon. Openings 4 are formed 25 through the edge portions of the base block to provide ventilation and prevent perspiration accumulating excessively beneath the base block upon the wearer's wrist. The outer side of the base block is preferably flat, as indicated at 5, and upon the said flat outer face of the base block I place a backing 6 which may be of any desired material but preferably will be of metal. This backing may be given any desired outline and in 30 the drawing is shown as octagonal, although it may be circular, elliptical, or of any other preferred shape. In the under side of the backing and extending longitudinally of the base block is a groove or passage 7 through

which the securing strap or ribbon 8 is 50 passed, the said strap or ribbon lying upon the base block, as clearly shown in Fig. 2, and being equipped with a buckle 9 at one end of any desired formation to be engaged by the free end of the strap beneath the 55 wearer's wrist so as to secure the article in place. The mirror 10 is placed directly against the outer face of the backing 6 and is held thereto by an overhanging rim 11 through which and the backing rivets 12 are 60 inserted to secure the rim and the backing to the base block. The rim 11 and the backing 6 may be embellished with any desired surface ornamentation so that an attractive article will be produced and the device may 65 or may not be provided with a cover 13 which will, of course, be of the same outline as the backing and the rim and will be hinged to the rim, as indicated at 14. A lining 15 of plush or some other soft material 70 may be provided upon the cover so as to cushion the impact of the cover upon the rim 11 and also protect the mirror against injury. The hinge 14 will preferably be of the well-known spring type by which the 75 cover will be yieldably held in either the closed or the open position.

From the foregoing description, taken in connection with the accompanying drawings, it will be seen that I have provided an 80 exceedingly simple device which may be worn without discomfort and which will not be so readily lost as the mirrors which are now commonly carried in purses.

Having thus described the invention, what 85 is claimed as new is:

1. An article of the character described comprising a base block, a backing secured upon the outer side of the base block, a mirror resting upon the backing, a rim secured upon the outer surface of the backing and overhanging the edge of the mirror, and a retaining strap passing between the backing and the base block and over the edges of the base block. 90

2. A device of the character set forth comprising a base block, a backing secured upon the base block and provided with a longi- 95

tudinal groove in its face opposed to the base block, a retaining strap passing through said groove and over the edges of the base block, and a mirror carried by said backing.

5 3. An article of the character set forth comprising a base block adapted to fit to the wrist of a wearer, means for retaining said base block upon the wearer's wrist, a back-

ing secured upon the base block, a mirror resting upon said backing, a rim secured 10 upon the backing and overhanging the edge of the mirror, and a cover hinged to said rim and adapted to extend over the mirror.

In testimony whereof I affix my signature.

SHERMAN HARROLD. [L.S.]
